UNITED STATES PATENT OFFICE

91,138

DESIGN FOR A DISPLAY CASE

Claude R. Kirk, Chicago, Ill.

Application September 21, 1933. Serial No. 49,304

Term of patent 3½ years

To all whom it may concern:

Be it known that I, CLAUDE R. KIRK, a citizen of the United States, residing at Chicago, in the county of Cook and State of Illinois, have invented a new, original, and ornamental Design for a Display Case, of which the following is a specification, reference being had to the accompanying drawing forming part thereof, and in which:

Fig. 1 is a plan view of the article showing my new design;

Fig. 2 is a front perspective view of the same; and

Fig. 3 is a side view thereof.

I claim:

The ornamental design for a display case as shown.

CLAUDE R. KIRK.
